UNITED STATES PATENT OFFICE

THEODORE C. MENGES, OF WATERLOO, IOWA, ASSIGNOR TO ASSOCIATED MANUFACTURERS COMPANY, OF WATERLOO, IOWA

CARBURETOR

Application filed May 9, 1928. Serial No. 276,401.

My invention relates to improvements in carburetors, and the objects of my improvements are these: first, to furnish a simple, inexpensive and effective carburetor which 5 while primarily designed for two cycle internal combustion engines, yet is equally useful for engines having other pluralities of cycles; second, to supply for the carburetor a fuel intake device having a check valve for preventing a return at times of fuel thereabove, 10 said check valve also functioning in case of back firing of the engine in preventing ignition of the contents of the fuel tank; third, to provide the carburetor with communicating fuel receiving and air intake chambers, the latter having an adjustable shutter whose maximum areal opening is much greater than the area of the carburetor delivery port for mixed fuel and air, whereby flooding may be 15 quickly prevented, and the combined chambers being adapted to retain a small residue of unused fuel after supply and engine draft, to permit quick pick up of fuel when the engine is running under a light load, or when 20 running idle; fourth, to so associate a needle valve with the fuel intake of the carburetor in connection with the special construction of the fuel receiving chamber of the latter, that fuel is delivered directly into said chamber 25 without possibility of a leakage past the remote mounting of the needle valve, and fifth, to supply a resiliently controlled valve for the passage from the mixing chamber to the delivery port of the carburetor, to prevent compressed fuel gas from returning 30 from such gas under compression in the crank-case of an engine with which the carburetor is in communication in certain types of engines.

40 All the above objects have been successfully accomplished in the device of my invention exemplified herein in the drawings, and in the appended description and claims.

In said drawings, both of the figures are 45 taken on a somewhat magnified scale for the sake of clearness, but the device may be furnished in any desired scale, and modifications thereof in any particular are nevertheless covered by the principles of my invention and the scope of the claims.

In the drawings, Fig. 1 is a vertical longitudinal section of the carburetor taken along the axis of the needle valve thereof, with a part of the fuel supply pipe broken away, and Fig. 2 is a top plan of the carburetor.

The body 1 of the carburetor has at the bottom a mixing chamber 2 from which arises a diminished passage 20 leading into a mixed fuel delivery chamber 21 thereabove 30 having in its side wall a lateral delivery passage and port 22 traversing the vertically elongated flat bracket body 4. This bracket body may have at top and bottom apertures 5 to receive headed screws or other securing means for mounting the carburetor upon an engine crank-case with the port 22 in communication with the interior of the crank-case, when the engine is of the two cycle type where the fuel gas and air mixed therewith are compressed initially in the crank-case by piston action and before delivery of the fuel through the usual by-pass port at times into the combustion chamber of the engine. The carburetor may, however, obviously supply the fuel through a valve-controlled or otherwise arranged inlet port of engines of other pluralities of working cycles.

The carburetor body includes integrally 30 the bowl or cup-shaped communicating part 3, the partially concave bottom 2' of the part 3 becoming flatly horizontally continuous with the flat bottom of the chamber 2, whereby in effect the cavity becomes a single elongated chamber. The top cover 36 of the cup part 3 has segmental openings around a central pintle 31 upon which is rockingly mounted a shutter 32 elongated outwardly to provide a handle, and which has also segmental openings 35 which may varyingly register with or communicate with said openings in the cover 36 according to an adjustment desired.

45 The mixing chamber 2 is supplied with fuel gases as follows. In a lateral bulge 6 of the carburetor body 1 is a closed top downwardly opening passage 7 interiorly threaded in its lower portion to seat the upper exteriorly threaded end of a supply pipe 9. A 100

narrower horizontal passage 8 leads from the passage 7 into the chamber 2 by way of the diminished passage 20 above the latter.

At the bottom of the vertical supply pipe 9 I position therearound a tubular valve-chamber 10 having a medial partition 12 with central apertured valve-seat 13 upon which normally rests a ball check-valve 14. Between the partition 12 and the imperforate bottom part 11 is a chamber whose side walls have large receiving openings separated by standards 15, said openings being circumferentially inclosed by finely meshed screen material 16, and the valve-chamber 10 is immersed in the liquid fuel of a tank not shown.

The delivery end of the passage 8 is controlled by a needle-valve 18 which traverses the passage 20 over the mixing chamber 2 and is threaded to be seated adjustingly in an interiorly threaded horizontal bore 17 leading oppositely through an elongated cylindrical portion 34 of the body 1 to project outwardly therefrom, said needle-valve having an end notch to permit adjustments, and having a locking wing-nut 19 mounted on its threaded stem.

It should be particularly observed that the mixing chamber 2, the intermediate fuel-receiving passage 20, and the valve-chamber 21 are located in relative superposition for an object to be disclosed.

The valve-chamber 21 contains a valve-head 28 whose upwardly directed stem 27 is loosely seated in a cavity 26 positioned axially in a headed screw closure 25 above. The upper hollow part 33 of the carburetor body 1 is cylindrical and contains at the top an interior thread 23 to receive the threaded diminished part 24 of the closure 25. The latter has a diminished cylindrical and depending part 29 around the stem 27 to seat a light helical compression spring 30 which is engaged between the lower face of the part 24 and the flat upper face of the valve-head 28. This spring normally keeps the valve 28 closed. In the drawing, Fig 1 shows the valve in its uppermost position as at the close of a fuel draft outwardly to the engine by way of the port 22.

Operation.—The screen 16 prevents small solid impurities from passing into the hollow of the valve-chamber 10, but allows free entry of the liquid fuel. The ball check-valve lifts when suction from the engine acts thereupon to let fuel pass into the tube 9, and passages 7 and 8. The needle valve 18 being opened, the fuel enters the space 20.

It will be well to mention here that small power-unit two-cycle gas engines are frequently employed in households for actuating washing machines and other driven appliances, and when these or other cycle engines are used it is very requisite that there be no leakage of liquid fuel, as readily occurs

around the stem of a needle-valve as ordinarily mounted in the carburetor. In my carburetor such leakage cannot take place, because I have caused the fuel to be delivered from the passage 8 past the needle point directly into the wide passage 20 to drop thence downwardly into the wider mixing chamber 2. As the latter is below the receiving space 20 and wholly below the seat 17 of the needle-valve 18, it is impossible that liquid fuel can enter the seat 17 and leak outwardly therefrom.

Furthermore, in the action of the engine, as the valve 28 is alternately lifted and dropped, the engine or crank-case thereof cannot become flooded from the contents of the chamber 2 at times. This is owing to the fact that I have supplied air-ports for the air receiving cup 3 whose combined areas under normal delivery of air are in their aggregate much larger than the cross sectional area of the carburetor delivery port 22. In the event that but a small air volume is being delivered into the cup 3 because of the restrictive action of the shutter 32, and symptoms of flooding occur, the operator may quickly rock the shutter to effect wider opening of the air ports so that the larger volume of entering air will prevent the flooding.

As the bottom of the chambers 2 and 2' is flat and horizontally continuous, any surplus of liquid fuel that may remain there is picked up by a succeeding suction. This is beneficial where an engine is running under a light load, because the charge of fuel gas in the mixture will be richer after picking up this surplus.

When a back-firing occurs in the crank-case, the ball check-valve 14 is closed, so there is no possibility of fire communicating to the contents of the fuel tank.

Having described my invention, what I claim as new, and desire to secure by Letters Patent, is:

1. A carburetor containing a mixing-chamber with imperforate bottom and sides and having a controllable air-port in its top, said carburetor having a valve-chamber in communication with the top of said mixing-chamber and having a delivery-port, a resiliently controlled valve controlling said valve-chamber inlet, said carburetor having a fuel nozzle delivering into the upper part of the mixing-chamber adjacent to the valve-seat of the resiliently controlled valve, a conduit leading into said carburetor to said nozzle, a valve-chamber in the outer end of said conduit in communication with a supply of liquid fuel, and said valve-chamber having a valve-seat and a check-valve for normally closing the valve-seat from above to prevent return of fuel and also to prevent ignition of the fuel below the valve-seat due to back-firing of the engine.

2. A carburetor containing a mixing-chamber with imperforate bottom and having an air-port in its top, said carburetor having a valve-chamber in communication with the top of said mixing-chamber and having a delivery-port, valvular means controlling said delivery-port, said carburetor having a fuel nozzle delivering horizontally into the upper part of the mixing-chamber adjacent to the valve-seat of said valve-chamber, said carburetor having a horizontal interiorly threaded opening across the upper part of the mixing-chamber and aligned with said nozzle, and a threaded needle-valve stem seated adjustably in said opening to cross the mixing-chamber and having a conical termination to enter and control the delivery of said nozzle, whereby liquid fuel delivered upon said conical termination enters the mixing-chamber at the top in a conical spray and wholly above the fuel supply in the lower part of the mixing-chamber.

In testimony whereof I affix my signature.
THEODORE C. MENGES.
